UNITED STATES PATENT OFFICE

168,843

CHAIR

Daniel R. Johnson, Los Angeles, Calif.

Application October 31, 1952, Serial No. 22,079

Term of patent 14 years

(Cl. D15—8)

To all whom it may concern:

Be it known that I, Daniel R. Johnson, a citizen of the United States, residing at Los Angeles, county of Los Angeles, and State of California, have invented a new, original, and ornamental Design for a Chair, of which the following is a specification, reference being had to the accompanying drawing, forming a part hereof.

Fig. 1 is a front elevational view of a chair, showing my new design;

Fig. 2 is a side elevation of the chair as seen from the right of Fig. 1;

Fig. 3 is a generally diagonal elevational view of the chair looking in the direction of the arrow 3 in Fig. 2.

I claim:

The ornamental design for a chair, substantially as shown.

DANIEL R. JOHNSON.
